UNITED STATES PATENT OFFICE.

JOHN A. WOLCOTT AND THEODORE C. SCHWARTZ, OF WYANDOTTE, MICHIGAN.

VALVE.

No. 913,866.

Specification of Letters Patent. Patented March 2, 1909.

Application filed June 17, 1908. Serial No. 438,908.

To all whom it may concern:

Be it known that we, JOHN A. WOLCOTT and THEODORE C. SCHWARTZ, citizens of the United States of America, residing at Wyandotte, in the county of Wayne and State of Michigan, have invented certain new and useful Improvements in Valves, of which the following is a specification, reference being had therein to the accompanying drawings.

10 Where one of a battery of boilers is temporarily out of service for repairs, it frequently occurs that steam from the companion boilers is inadvertently admitted thereto from the other boilers while workmen are 15 still engaged thereon, often trapping them and causing serious, oft-times fatal accidents.

This invention relates to a valve adapted to be placed in the steam pipe or like cross connection between boilers, which is inaccessible for ordinary manipulation from without the pipe and cannot be opened while there is any steam in the pipes, and at the same time, does not form an obstruction thereto when not in use or unnecessarily 25 complicate the boiler fittings and piping.

The invention consists in the matters hereinafter set forth, and more particularly pointed out in the appended claims.

In the drawings, Figure 1 is a view in cross-section of a valve embodying features of the invention. Fig. 2 is a view in longitudinal section of the valve. Fig. 3 is a view in elevation showing the valve casing in position. Fig. 4 is a view in detail of a valve 35 closure.

Referring to the drawings, 1 indicates a casing having end flanges 2 corresponding in internal and preferably also in external diameter to the flanges 3 of a pipe line in 40 which it is placed and secured in conventional manner. A hand-hole plate 4 is removably fastened, as by cap screws 5 or the like, over a lateral opening which is the full width of the casing interior and is slightly 45 wider than the inner diameter of the flanges; each of the latter has an inner annular rib 6 which forms a valve seat. A closure consisting of a plate 7 with annular rabbet or channel 8 filled with soft metal as copper or 50 the like, adapted to mate with either of the ribs 6, has a diametrically disposed bridge 9 moving in longitudinally slotted guide studs 10 and in a central boss 11, pins 12 engaging slots in the bridge limiting its movement, 55 and a spider 13 with notched periphery for engagement of a spanner wrench or the like,

which has screw-threaded engagement with the boss 11, whereby the bridge may be forced against the casing when the closure is at seat and thereby hold the latter firmly in place. A hand grip is formed by a suitable aperture 14 near the plate end by which it may be readily taken in and out of the casing.

In operation, the casing is inserted in a line of pipe connecting two boilers. When 65 either is to be repaired, the usual cut-off or controlling valve, as 15, is closed, and when the boiler is blown off, the casing hand-hole plate is removed, the closure placed therein, with its face toward the boiler under pressure, and the bridge holds the closure to seat, the spider being screwed home by proper manipulation of a suitable bar or wrench. The hand hole plate is then replaced. Thus 70 any accidental handling or tampering with 75 the regular gate does no damage to persons at work on the "dead" boiler, as the steam cannot get through the auxiliary valve which is not open to manipulation. Nor can it be opened without first removing the hand 80 hole plate, which therefore opens the pipe, and necessitates the proper shutting of the regular valve before any manipulation of the spider within the casing. By removing and replacing the closure in reverse position, the 85 adjacent boiler may be taken care of. When not in use, the closure is taken out of the casing which thus forms no obstruction to the steam.

Obviously details of construction may be 90 changed without departing from the spirit of the invention and we do not care to limit ourselves to any particular form or arrangement of parts.

When used to cut off any one of a battery 95 of boilers, a casing is inserted in the pipe connecting each boiler with the main line between the boiler and the shut-off valve.

What we claim as our invention is:—

1. A valve for the purposes described comprising a casing and a closure adapted to be detachably held to seat therein by means carried by the closure and completely housed by the casing when the closure is seated, the closure and holding means being bodily removable from the casing, and the casing being adapted to form a substantially unobstructed coupling in a pipe line when the said members are withdrawn.

2. A valve for the purposes described comprising a casing adapted to be permanently secured as a coupling between adjacent ends

2

of sections of a pipe line, and a closure adapted to seal the casing when placed therein and provided with means adapted to engage the casing, and hold the closure in place, said closure and holding means being removable as a unit from the casing, and being completely housed thereby when the closure is seated.

3. A valve for the purposes described, comprising a casing, a closure, and means on the closure adapted to engage the casing and to force the closure to seat, the closure and holding means being bodily removable as a unit from the casing and being completely inclosed thereby when in place.

4. A valve for the purposes specified comprising a casing having circular end flanges each having an annular rib forming a valve seat on its inner face, a hand hole plate detachably secured on a lateral opening in the casing, a closure adapted to be seated against either one of the flange seats, a bridge movable on the closure adapted to bear against the opposite valve seat and a spider on the closure adapted to force the closure and bridge apart, the closure and bridge being bodily removable through the hand hole plate opening.

5. A valve for the purposes described comprising a casing, a hand hole plate detachably secured over a lateral opening in the casing, a pair of circular coupling flanges

on the casing ends, an annular rib on the inner face of each flange forming a valve seat, a closure plate having a face adapted to close on either one of the valve seats, a screw-threaded boss on the other face of the plate, a bridge longitudinally movable on the boss adapted to bear at its ends on the adjacent valve seat, a spider having screw-threaded engagement with the boss adapted to force the bridge outwardly, and a pair of studs on the plate having slots in their outer ends engaged by the bridge.

6. A valve for the purposes described, comprising a casing having a lateral aperture, a cover therefor, a closure adapted to be inserted through the aperture, and means adapted to force the closure to seat in the casing, said means being adapted to be manipulated only when the cover is removed, the closure and holding means being bodily removable as a unit from the casing through the aperture and being completely housed by the casing when in operative position with the cover in place.

In testimony whereof we affix our signatures in presence of two witnesses.

JOHN A. WOLCOTT.
THEODORE C. SCHWARTZ.
